UNITED STATES PATENT OFFICE.

HENRY A. HOUSE, OF BRIDGEPORT, CONNECTICUT.

IMPROVEMENT IN SUSPENDER-BUCKLES.

Specification forming part of Letters Patent No. 147,325, dated February 10, 1874; application filed November 20, 1873.

To all whom it may concern:

Be it known that I, HENRY A. HOUSE, of Bridgeport, in the county of Fairfield and State of Connecticut, have invented a new and Improved Suspending-Clasp for Connecting Suspenders with Pantaloons, Drawers, and other similar articles of wearing apparel; and I do hereby declare that the following is a full, clear, and exact description thereof, reference being had to the accompanying drawings making part of this specification, in which—

Figure 1 is a perspective view, showing the straps of a suspender attached, by my improved clasp, to the waistband of a pair of pants. Fig. 2 is a perspective back view of the clasp. Fig. 3 is a section taken vertically through the clasp, showing also in section the bands of the pants and drawers held by said clasp.

Similar letters of reference indicate corresponding parts in the several figures.

The object of this invention is to provide a suspender-clasp which will clamp the band of the pants, or, if desired, the bands of the pants and drawers, as will be hereinafter explained, and which may be attached by a hook to the straps of the suspenders.

The following description of my invention will enable others skilled in the art to understand it.

In the accompanying drawings I have represented merely for illustration a suspender, A, which is connected to straps B B, by means of a clasp, C. The straps B B may have the usual button-holes, or eyelets may be inserted in them for the purpose of receiving the hooks E of my improved clasps. Each hook E will be permanently attached to an eye, a, formed on the clasp-plate D. This clasp-plate D may be stamped out of a single piece of metal, and it is bent in the form of the letter U, with an opening, g, and with two curved portions, b b, the ends of which latter are turned so as to form hinging-eyes e e. To these eyes I attach a clamp, G, which is an open frame stamped out of a single piece and bent so as to form a clamping portion or tongue, a pintle, and a

handle or lever, as clearly shown in Figs. 2 and 3.

I thus construct the clasp of these parts, to wit: A hooking portion, E, which might be formed on the clasp-plate D, and a hinged clamp, G, through which latter an opening, g, is made for allowing a portion of the pants, or both the drawers and pants, to sink through it when the tongue of the clamp G gripes them against the longest or outside portion of the buckle-plate D, (as shown in Fig. 3,) thus affording a very firm hold.

To apply my clasp to the waistband of the pants, or the pants and drawers, or the latter alone, it is only necessary to introduce the edge of the waistband between the short and long portions of the clasp-plate, and then to force the clamp into position shown in full lines, Fig. 3.

If desirable, the biting-edge of the clamp G may be serrated, or it may have a tongue formed on it opposite the opening g, for the purpose of forcing the material which it is holding into the opening g, as shown in Fig. 3.

The advantages of my improvement are obvious; for instance, it renders unnecessary the use of suspender-buttons on the waistband or loops on the drawers, and also admits of the use of eyelets, metallic, or stitched on the straps of the suspenders. To detach the clasp, press down the handle of the clamp G to the position indicated by dotted lines, Fig. 3.

Having described my invention, what I claim as new, and desire to secure by Letters Patent, is—

1. As a new article of manufacture the suspender-clasp herein shown, made out of two pieces of metal, constructed or shaped and pivoted together, as and for the purpose set forth.

2. The hook E attached to the upper part of the piece D of the suspender-clasp D G, as and for the purpose herein described.

HENRY A. HOUSE.
